UNITED STATES PATENT OFFICE.

JOHN C. KOPF, OF BELLEVUE, PENNSYLVANIA, ASSIGNOR TO THE DUFF MANUFACTURING COMPANY, OF PITTSBURGH, PENNSYLVANIA, A CORPORATION OF PENNSYLVANIA.

JACK.

1,373,894.

Specification of Letters Patent. Patented Apr. 5, 1921.

Application filed October 22, 1919. Serial No. 332,512.

To all whom it may concern:

Be it known that I, JOHN C. KOPF, a citizen of the United States, and resident of the borough of Bellevue, in the county of 5 Allegheny and State of Pennsylvania, have invented a new and useful Jack, of which the following is a specification.

An object of the invention is to provide a simple, compact and serviceable self-locking rack and pinion jack. A further object 10 is to enable a jack of this description to be operated from a distance and at a convenient height. To these ends, the jack comprises a rack-bar, preferably circular 15 and free to turn in the stand, having downward-facing buttress teeth, and a convex spiral face pinion supported in tilted position in engagement with the rack, the axis of the pinion inclining upward and forward 20 and being preferably prolonged by a long rotary detachable handle.

Still another object is to enable a self-locking operating pinion of a jack to be disengaged for quick-lowering, and normally 25 and under load to be held securely in place.

In the accompanying drawings, forming a part hereof:

Figure 1 is a side elevation of the jack;

Fig. 2 is a front elevation thereof, that is 30 to say an elevation looking at the handle side;

Fig. 3 is a central vertical section taken in the plane of the axis of the pinion, showing the crank-handle with intermediate portions broken away;

Fig. 4 is a fragmentary front elevation, looking at the interior of the pinion case, with the bonnet and pinion removed;

Fig. 5 is a horizontal section on the line 40 5-5 of Fig. 1;

Fig. 6 is a transverse section taken on the angular line 6-6 of Fig. 3;

Fig. 7 is a face view of the pinion;

Fig. 8 is a vertical section illustrating a 45 modification; and

Fig. 9 is a front elevation of Fig. 8.

The jack has an upright hollow columnar stand 2, with base 3. The interior of the stand forms a rack channel 4, circular in 50 cross-section, for laterally supporting and guiding a round rack-bar 5 bearing a lifting seat 5^a. Said rack-bar is formed with circumferential rack teeth 6 of buttress formation, that is to say, triangular in

cross-section with sloping upper sides and 55 approximately horizontal or square under sides.

A series of said teeth are meshed simultaneously by a spiral buttress thread 7 on the face of a tilted pinion disk 8, which is 60 housed in a frame extension 9 on the upper part of the stand. The spiral face of said pinion is slightly convexed, or straight sloped from the inner margin of the annular threaded area downward to the outer 65 margin; and the inclination of the axis of the disk is such in relation to this slope that all the convolutions in the upper part mesh with the rack teeth, while in the lower part the threads are out of engagement. 70

Thus, turning the pinion in one direction will exert a powerful raising pressure upon the rack, and with comparatively little friction owing to the line contact. The gearing is self-locking against descent, and, the rack 75 being free to turn and present fresh portions of its teeth to the pinion, wear is distributed and minimized. The buttress form of the teeth and the engagement of a substantial number thereof at one time insures great 80 strength.

In the form of the invention illustrated in Figs. 1 to 6, the pinion 8 is secured on the inner end of an inclined driving shaft member 10, having a journal portion 11, which 85 is rotatably supported in a bearing 12 in a bonnet 13 screwed into the open end of the chamber 9. This construction permits of the ready assembling of the mechanism, the entrance which is closed by the bonnet being 90 large enough to admit the pinion. The pinion and shaft are held against axial displacement by a hub 14 and collar 15 embracing the bearing portion of the bonnet.

The pinion is directly supported against 95 the load by an arcuate bearing ledge 16 formed on the bottom of the chambered frame portion 9, in position to constitute a rest for the smooth circular periphery of the disk.

The outer end of the shaft member 10 has a cross-pin 17, or is otherwise formed, to receive the socket end 18 of a long detachable rotary crank-handle 19, which when in place extends upward to such height that the 105 user can operate the jack from a distance and without getting close to the ground.

Figs. 8 and 9 illustrate a construction

wherein a self-locking pinion for operating the rack-bar of a jack is displaceable at will, so that it can be disengaged to permit of quick lowering in the absence of load. This 5 may be accomplished in specifically different ways within this part of the invention. In the construction illustrated the lateral chambered frame extension 9^a containing the pinion is hinged at the bottom to the stand 10 body 2^a, on a transverse pivot 20. A suitable readily-operated fastening 21, at the top, secures the movable frame part in the normal position, and permits it to be swung downward when desired. The relations are 15 such that with load upon the rack, the pressure of the rack teeth upon the thread of the pinion tends to draw the pinion toward the

rack, and thus opposes accidental disengagement when lifting.

In this construction the back wall of the 20 case 9^a is made integral, as the pinion can be placed upon the end of the shaft from within after the shaft has been inserted through its bearing.

What I claim as new is:

A jack comprising a stand, a rack-bar guided therein and carrying a lifting seat, and operating means comprising a tilted convex spiral face pinion mounted in the stand and meshing at its upper part with 30 the rack, the periphery of the pinion being smooth and circular, and the stand having a bearing beneath said periphery.

JOHN C. KOPF.
